Primary Examiner — T Chase Nelson*Assistant Examiner* — Sydney Margaret Parsley(57) **CLAIM**

The ornamental design for a ladder mount tool holder, as shown and described.

DESCRIPTION

FIG. 1 is a front view of a ladder mount tool holder showing my new design;

FIG. 2 is a rear view of the ladder mount tool holder;

FIG. 3 is a left side view of the ladder mount tool holder;

FIG. 4 is a right side view of the ladder mount tool holder;

FIG. 5 is a top view of the ladder mount tool holder;

FIG. 6 is a bottom view of the ladder mount tool holder;

FIG. 7 is a top front side perspective view of the ladder mount tool holder; and

FIG. 8 is a top front side perspective view of the ladder mount tool holder in use; and,

FIG. 9 is a cross-sectional view taken along line 9-9 of FIG. 5.

The broken lines in FIG. 8 are illustrative of environmental structure forming no part of the claimed design.
